Primary Examiner — George D. Kirschbaum(74) *Attorney, Agent, or Firm* — Polson Intellectual Property Law, PC; Margaret Polson(57) **CLAIM**

The ornamental design for a climbing frame, as shown and described.

DESCRIPTION

FIG. 1 is a front, left side isometric view of our new design for a climbing frame.

FIG. 2 is a top side plan view of FIG. 1.

FIG. 3 is a bottom side plan view of FIG. 1.

FIG. 4 is a front side elevation view of FIG. 1.

FIG. 5 is a back side elevation view of FIG. 1.

FIG. 6 is a right side elevation view of FIG. 1

FIG. 7 is a left side elevation view of FIG. 1; and,

FIG. 8 is a front, left side isometric view of our new design for a climbing frame.

The broken line showing is included for the purpose of illustrating portions of the "article" and forms no part of the claimed design.

1 Claim, 8 Drawing Sheets(56)
